CLAIM

We claim the ornamental design for an information handling system dock, as shown and described.

DESCRIPTION

FIG. 1 is a front perspective view of the information handling system dock comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; and, FIG. 8 is a front perspective view thereof in an environment of use supporting a portable information handling system. Broken lines shown in the drawings illustrate portions of the information handling system dock and form no part of the claimed design.
